UNITED STATES PATENT OFFICE

166,774

COFFEE SERVER

William J. Russell, New Britain, Conn., assignor
to Landers, Frary & Clark, New Britain, Conn., a corporation of Connecticut

Application March 17, 1952, Serial No. 18,933

Term of patent 14 years

(Cl. D44—26)

To all whom it may concern:

Be it known that I, William J. Russell, a citizen of the United States, residing at New Britain, in the county of Hartford, State of Connecticut, have invented a new, original, and ornamental Design for a Coffee Server, of which the following is a specification, reference being had to the accompanying drawing, forming a part hereof.

In the drawing:

I claim:

The ornamental design for a coffee server, as shown.

WILLIAM J. RUSSELL.
